UNITED STATES PATENT OFFICE.

HENRY RENY, OF BIDDEFORD, MAINE.

PISTON-VALVE FOR MUSICAL INSTRUMENTS.

SPECIFICATION forming part of Letters Patent No. 245,863, dated August 16, 1881.

Application filed June 4, 1881. (Model.)

To all whom it may concern:

Be it known that I, HENRY RENY, of Biddeford, in the county of York and State of Maine, have invented certain useful Improvements in 5 Valves for Musical Instruments, of which the following is a specification.

The object of my invention is to provide a new and improved valve for musical instruments, such as trumpets, cornets, &c., which 10 has a smaller stroke than the similar valves in use heretofore, and is thus much more convenient for the musician or performer.

The invention consists in a valve for musical wind-instruments, which valve has its piston 15 constructed with oblong or flat transverse apertures in place of the circular apertures, as made heretofore, the apertures in the cylinders or piston-tubes and the cross-sections of the connecting-pipes being the same as the apertures of the piston.

In the accompanying drawings, Figure 1 is a longitudinal elevation of a cornet provided with my improved valves. Fig. 2 is a longitudinal elevation of the valve casing or chamber. Fig. 3 is a longitudinal sectional elevation of the same, showing the valve-piston raised. Fig. 4 is a longitudinal sectional elevation of the same, showing the valve-piston depressed. Fig. 5 is a cross-sectional elevation 20 of the same on the line *x x*, Fig. 3. Fig. 6 is a cross-sectional elevation of the same on the line *y y*, Fig. 4; and Fig. 7 is a cross-sectional elevation of the same on the line *z z*, Fig. 4.

Similar letters of reference indicate corresponding parts.

The valve-piston A is contained in the valve-chamber B, and is pressed upward by a spiral spring, C, surrounding the piston-rod D, provided with an end or finger plate, E. This 40 valve-piston is provided with transverse and diagonal perforations or apertures F and G and H, which establish connections between the pipes or tubes connecting the several valve-chambers B, which are provided with apertures J, K, and L, over which the ends of these connecting-pipes fit. As shown in Figs. 2, 3, and 5, the apertures J of the valve-chamber B are connected by the perforation or opening H, and the other apertures of the valve-chamber are closed; but if the piston is depressed, 45 as shown in Figs. 4, 6, and 7, the apertures L and one of the apertures J are connected by the perforation F, and the other aperture J and the aperture K are connected by the per-

foration G. The wind thus passes through 55 the instrument in a different manner, and a change of the tone is effected; but in order to change the position of the valve-piston, the piston-rod D must be depressed, and if the apertures, perforations, pipes, &c., are all circular, as constructed heretofore, the piston-rod and the piston must be depressed a distance equal at least to the diameter of the tube or corresponding aperture, and as this tube and apertures are of considerable diameter, 60 especially in large instruments, it strains the fingers of the performer very much. If the same results could be obtained with a smaller stroke of the piston, the performer or musician would be relieved considerably. For this purpose I do not construct the apertures, perforations, and connecting-pipes of the valve-chamber with a circular cross section, as has been customary heretofore; but I make them oblong—that is to say, the width is increased 70 and the height is decreased; but the area of cross-section is the same as that of the circular aperture or pipes; but the valves can thus be operated with a much smaller stroke, and the desired object is attained.

The tubes can be made in the ordinary manner, but must be flattened, so as to fit over the apertures in the valve-chambers.

Having thus fully described my invention, I claim as new and desire to secure by Letters 85 Patent—

1. In a valve for musical instruments, the valve-pistons constructed, substantially as herein shown and described, with oblong apertures, as and for the purpose set forth.

2. In a valve for musical instruments, the combination, with the valve-casing B, provided with oblong apertures, of the valve-piston A, provided with oblong perforations, substantially as herein shown and described, and for the purpose set forth.

3. In a musical instrument, the combination, with the valve-casing B, provided with oblong apertures, of the valve-pistons A, with oblong perforations, and of the connecting-tubes M, which are oblong in cross-section, substantially as herein shown and described, and for the purpose set forth.

HENRY RENY.
